CLAIM

The ornamental design for a Junctional hemorrhage control plate, as shown and described.

DESCRIPTION

FIG. 1 is a top perspective view of a first embodiment of the present invention.

FIG. 2 is a bottom perspective view of the embodiment shown in FIG. 1.

FIG. 3 is a perspective view of the embodiment shown in FIG. 1, with environment.

FIG. 4 is a perspective view of the embodiment shown in FIG. 1, with environment.

FIG. 5 is a top view of the embodiment shown in FIG. 1.

FIG. 6 is a bottom view of the embodiment shown in FIG. 1.

FIG. 7 is a left-side view of the embodiment shown in FIG. 1, the right-side view being a mirror image.

FIG. 8 is a front-end view of the embodiment shown in FIG. 1, the rear-end view being a mirror image.

FIG. 9 is a top perspective view of a second embodiment of the present invention.

FIG. 10 is a bottom perspective view of the embodiment shown in FIG. 9.

FIG. 11 is a top view of the embodiment shown in FIG. 9.

FIG. 12 is a bottom view of the embodiment shown in FIG. 9.

FIG. 13 is a left-side view of the embodiment shown in FIG. 9, the right-side view being a mirror image; and,

FIG. 14 is a front-end view of the embodiment shown in FIG. 9, the rear-end view being a mirror image.
